UNITED STATES PATENT OFFICE.

ARTHUR G. MARSHALL, FORMERLY KNOWN AS OTTO GEORGE MARQUYL, OF PITTSBURGH, PENNSYLVANIA.

DESIGN FOR A CABINET.

Application filed November 23, 1921. Serial No. 517,365. Term of patent 7 years.

To all whom it may concern:

Be it known that I, ARTHUR G. MARSHALL, formerly known as OTTO G. MARQUYL, a citizen of the Republic of Switzerland, I having filed an application for citizenship of the United States, residing at Pittsburgh, county of Allegheny, and State of Pennsylvania, have invented a new, original, and ornamental Design for Cabinets, of which the following is a specification, reference being had to the accompanying drawing, forming part thereof.

The figure is a perspective view of a cabinet showing the new design.

I claim:

The ornamental design for a cabinet, as shown.

ARTHUR G. MARSHALL.
